UNITED STATES PATENT OFFICE.

ARTHUR V. A. McHARG, OF NEW YORK, N. Y., ASSIGNOR TO THOMAS E. MURRAY, OF NEW YORK, N. Y.

ELECTRIC CUT-OUT.

1,084,703.

Specification of Letters Patent. Patented Jan. 20, 1914.

Application filed April 30, 1913. Serial No. 764,491.

To all whom it may concern:

Be it known that I, ARTHUR V. A. McHARG, a citizen of the United States, residing at New York, in the county of New York and State of New York, have invented a certain new and useful Improvement in Electric Cut-Outs, of which the following is a specification.

The invention is a cut-out block designed more particularly for use in a three-wire system. A plurality of mutually insulated bus-bars extend through and across the base block. Above said bars and insulated therefrom are pairs of contacts. Circuit terminals of the system are connected to one member of each pair of contacts. The remaining members of said pairs are respectively connected to the bus-bars. A multiple switch lever pivoted on the base block carries a plurality of separable fuse-plugs, so arranged that when the lever is swung forward, said plugs are brought between the pairs of contacts to close circuit, and when the lever is swung back, said plugs are moved out of circuit and can readily be removed from said lever. The three conductors of the system are thus fused or de-fused by a single movement of the lever, and individual fuses may be readily removed and replaced while the circuit is open.

The invention consists in the construction hereinafter more particularly pointed out.

In the accompanying drawings—Figure 1 is a section on the line α , α of Fig. 2. Fig. 2 is an end elevation. Fig. 3 is a top view of the base block.

Similar numbers and letters of reference indicate like parts.

The base block 1 is preferably of refractory insulating material, such as porcelain, and has two side walls 2, 3 and two intermediate partitions so as to divide the space between said walls into three channels 4, 5, 6. Extending across said channels and passing through the walls 2, 3 and partitions are three superposed bus-bars 7, 8, 9, mutually insulated by plates 10, 11 of insulating material in each channel, as hereinafter more particularly described.

13, 14, 15 are three circuit conductors having at their ends metallic thimbles provided with laterally projecting arms 16, 17, 18.

Referring first to channel 4: In said chan-

nel is a block 19 of insulating material having a downward extension 20 on one side which fits against the edges of the bus bars 7, 8, 9, as shown in Fig. 1. A metal plate 21 extends over the top of block 19 and along the outer side of downward extension 20. To this last-named portion of plate 21, the arm 16 on conductor 13 is secured by the screw 22. The plate 21 carries a vertical spring contact plate A, Fig. 3. On top of block 19 and facing contact plate A is a contact plate B, carried by a metal plate 23 which extends down over the right hand edge of block 19, as shown in Fig. 1, and then under said block and between the same and bus-bar 9. It will be obvious that by closing circuit between plates A and B, electrical connection is established from conductor 13 to bus-bar 9.

Referring to channel 5: The arm 17 of conductor 14 is connected to a plate 24, Fig. 3, similar to 21, on a block 25 similar to 19, which plate carries the vertical spring contact C, Fig. 3. On said block 25 and facing contact plate C is a contact plate D, carried by a metal plate 26 which extends down over the right hand edge of block 25 and enters between the bus-bar 8 and the insulating separating piece above said block, as shown in dotted lines in Fig. 1. Therefore, by closing circuit between plates C and D, electrical connection is established from conductor 14 to bus-bar 8.

Referring to channel 6: The arm 18 of conductor 16 is connected to a plate 27, similar to plates 21 and 24, on a block 28 similar to blocks 19 and 25, which plate carries a vertical spring contact E, Fig. 3. On said block 28 and facing contact plate E is a contact plate F carried by a metal plate 29 which extends down over the right hand edge of block 28 and enters between the bus-bar 7 and the insulating separating piece above said bar, as shown in dotted lines, Fig. 1. Therefore, by closing circuit between plates E and F, electrical connection is established from conductor 16 to bus-bar 7.

The aforesaid electrical connection between the contacts A, B, C, D and E, F is effected by fuses G which are supported on plugs H of insulating material, over the upper thin edge of which plugs said fuses extend. When a plug is in place between the members of any of said pairs of contacts, the

arms of the fuse on opposite sides of said plug meet said contacts. In order to move the fuse plugs simultaneously into and out of position between said contacts, I provide 5 a rock shaft 30, journaled on the walls 2, 3, and having three arms 31, 32, 33, which are split at their ends to tightly fit in openings in said plugs. Said arms have upward extensions whereby they are connected to a bar 10 34 which carries an operating handle 35, by means of which handle said rock shaft 30 may be vibrated for the purpose above stated. Said bar 34 also carries a bracket 36, to which is secured a metal shield 37, 15 divided by partitions 38 into three compartments corresponding to channels 4, 5, 6 and lined with asbestos. Said shield protects the hand of the operator from the explosion of a fuse during manipulation of the handle 20 35, and also provides barriers between the fuses to prevent the explosion of one fuse injuring either of the other two fuses.

I claim:

1. A base block, a plurality of mutually insulated bus-bars extending transversely through said block, a plurality of pairs of contacts supported above and insulated from said bus-bars, means for connecting corresponding members of said pairs of contacts, 25 each to a different bus-bar, circuit terminals connected respectively to the remaining members of said pairs of contacts, and a multiple switching device for closing circuit between the members of said pairs.
2. A base block, a plurality of mutually insulated bus-bars extending transversely through said block, a plurality of pairs of contacts supported above and insulated from said bus-bars, means for connecting corresponding members of said pairs of contacts, 30 each to a different bus-bar, circuit terminals connected respectively to the remaining members of said pairs of contacts, a plurality of fuse-plugs, each coöperating with one of said pairs of contacts, and means for simultaneously moving said fuse-plugs into and out of coöperative relation with said contacts.
3. A base block, a plurality of mutually insulated bus-bars extending transversely through said block, a plurality of pairs of contacts supported above and insulated from said bus-bars, means for connecting corresponding members of said pairs of contacts, 35 each to a different bus-bar, circuit terminals connected respectively to the remaining members of said pairs of contacts, a pivoted multiple switch lever, and a plurality of fuse-plugs on said lever, each plug coöperating with one of said pairs of contacts.
4. A base block, a plurality of mutually insulated bus-bars extending transversely through said block, a plurality of pairs of

contacts supported above and insulated from said bus-bars, means for connecting corresponding members of said pairs of contacts, 65 each to a different bus-bar, circuit terminals connected respectively to the remaining members of said pairs of contacts, a pivoted multiple switch lever, and a plurality of fuse-plugs removably supported upon said lever, each plug coöperating with one of said pairs of contacts.

5. A base block, a plurality of mutually insulated bus-bars extending transversely 75 through said block, a plurality of pairs of contacts supported above and insulated from said bus-bars, means for connecting corresponding members of said pairs of contacts, each to a different bus-bar, circuit terminals 80 connected respectively to the remaining members of said pairs of contacts, a multiple switch lever having a plurality of projecting arms, and a plurality of removable fuse-plugs, provided with openings receiving said 85 arms, and coöperating with said pairs of contacts.

6. A base block, a bus-bar extending transversely through said block, a pair of contacts supported above and insulated from 90 said bus-bar, a circuit terminal connected to one member of said pair of contacts, a U-shaped conducting strip having one arm connected to the other member of said pair of contacts and its other arm in contact with 95 said bus-bar, and movable means for closing circuit between said contacts.

7. A base block, a pair of contacts thereon, a fuse carrier coöperating with said contacts, a rock shaft on said block, an operating lever therefor, an arm on said shaft engaging said fuse carrier, and a box-shaped shield carried by said rock shaft and receiving the upper portion of said carrier.

8. A base block, a plurality of pairs of 105 contacts thereon, fuse carriers coöperating with said pairs of contacts, a rock shaft on said block, an operating lever therefor, arms on said shaft engaging said carriers, a box-shaped shield carried by said rock shaft, and 110 partitions in said shield dividing the same into compartments respectively receiving the upper portions of said carriers.

9. A base, a plurality of bus-bars thereon, a plurality of pairs of contacts, each having 115 one member connected to one of said bus-bars, circuit terminals connected to the other members of said pairs, fuse plugs adapted to enter and close circuit between said contacts, and a support for said plugs movably secured to said base and operable to bring said plugs into and out of coöperative relation 120 with said contacts.

10. A base, a plurality of bus-bars thereon, a plurality of pairs of contacts, each 125 having one member connected to one of said

bus-bars, circuit terminals connected to the other members of said pairs, a bell-crank lever pivoted on said base, and fuse plugs on said lever; the said plugs entering and closing circuit between said contacts.

11. A base, a pair of contacts thereon, a bell-crank lever pivoted on said base, and a fuse plug on one arm of said lever; the said

plug entering and closing circuit between said contacts.

In testimony whereof I have affixed my signature in presence of two witnesses.

ARTHUR V. A. McHARG.
